UNITED STATES PATENT OFFICE.

HENRY WALKER, OF WELLINGTON, NEW ZEALAND.

MAIL-MARKING MACHINE.

1,214,243.

Specification of Letters Patent. Patented Jan. 30, 1917.

Application filed January 7, 1915. Serial No. 1,031.

To all whom it may concern:

Be it known that I, HENRY WALKER, a subject of the King of Great Britain, residing at Wellington, New Zealand, have invented certain new and useful Improvements 5 in Mail-Marking Machines, of which the following is a specification.

This invention has for its object the provision of a silent running mail marking machine which will automatically receive mail from a facing table of the ordinary kind, but preferably to work in conjunction with a novel apparatus attachable to an ordinary wooden post office table constituting a feeding trough the said attachment being composed of a number of units adapted to the length of the table and provided with extensible supporting means at intervals.

The machine is also adapted by the removal of certain parts to be used for hand feeding of faced mail if required.

The leading features of this invention are a feeding trough in units adjustable in height to suit the facing tables used for the 25 reception of mail matter, a guide plate at an acute angle to the letter path in combination with a belt on the opposite side of the path together with rollers to receive mail matter from the feeding trough and also primary 30 and secondary feeding and separating rollers with the marking roller disposed on the right hand side of the letter path. There is also an additional guide plate and feeding roller at the end of the feeding trough next 35 the mail marking table and the feeding belt in the feeding trough is extended therefrom up to the second separator and feed rollers on the mail marking table.

The invention consists in these features 40 and in the features and combination and arrangement of parts hereinafter described and more particularly set forth in the claims.

The invention is illustrated in the accompanying drawings in which—

45 Figure 1 is a general view in perspective of a mail marking machine comprising the invention. Fig. 2 is a plan of the marking table and parts thereon. Fig. 3 is an elevation of the marking table and parts thereon 50 illustrated in Fig. 2. Fig. 4 is a plan through A—B of Fig. 3, and shows the belt driving arrangement. Fig. 5 is an enlarged view of the first separator roller, adjacent belt pulley and part driving mechanism. 55 Fig. 6 is a section showing part of the feed-

ing trough, the belt therein and the first separator roller. Fig. 7 is a cross section of the feeding trough. Fig. 8 is a front view of the feeding and tension rollers. Fig. 9 is a plan of the feeding and tension rollers. 60 Fig. 10 is a front view of the back pressure roller, type roller and inkpad roller. Fig. 11 is a modification showing a supplementary guide and feeding roller in the feeding trough. Fig. 12 is a sectional elevation 65 showing the feeding trough belt carried forward to the second separator roller.

Mail matter tipped on to the facing table (1) from the receiving boxes is arranged 70 with the stamped edge downward and rearward in bunches and dropped by operators working side by side at the facing up table into the feeding trough (2) on to the feeding belt 7 therein. The feeding trough is in units of which one is illustrated and may be 75 made of any desired length by adding the necessary number of units. These units are adjustable in height by means of the nuts 12 screwing on the threaded upper ends of the standards, (11). The feeding trough abuts 80 on the mail marking table (25) and it having been found in practice that mail matter has a tendency to catch between the first separator roller (42) and the end of the feeding trough the inner wall of the feeding trough 85 has a continuation (58) which projects over the end of the table (25) and is slotted to allow of the first separator roller 42 just passing through it thus preventing mail matter catching as described. The feeding belt 90 7 passes over pulleys such as 8 and 9 and is kept taut by a pulley 14 pivoted in a bracket 15 and is driven by belting from any convenient source of power. The feeding belt 95 7 is continued as shown in Fig. 12 on a level with the mail marking table as far as the second separator roller 65 for the purpose 100 of assisting to forward mail matter that may occasionally halt in the letter path. A guide plate 110 with spring adjustment is placed at one side of the feeding trough and a feeding roller 111 on the other side is driven 105 from the feed belt pulley 29. This combination insures a partial separation of the mail matter before it reaches the first separator 110 roller (42).

A feeding belt (72) running around the belt pulleys (29) and (62) is kept at the required tension by means of the spring adjustable tension pulley (76) situated mid- 115

way of the belt pulleys which coöperating with the feeding roller (74) carries the mail already roughly separated by the first separator roller (42) forward past the guide plate (81) which is adjustable by spring (82) so that the mail is converged by the guide plate toward the second separator roller (65) the forward end of the guide plate (81) coating with the belt (72) also acting as a separator. The mail matter carried forward to the second separator roller (65) is there separated and passed by the impetus given by the feeding belt 72 to the type roller (84) which is disposed on the right hand side of the letter path. The mail matter is marked in the usual way and carried forward and stacked on the inclined plate 104 in the usual manner.

The separator rollers (42) and (65) rotate so that the surfaces which contact with the letters move in the opposite direction from that in which the letters are moving and the feed rollers rotate forward along the letter path. These rollers and the type and ink rollers are driven from pulley 39 on driving spindle 22 on which driving wheel 23 is driven from any convenient source of power. A belt 38 on pulley 39 drives pulley 34 see Fig. 4 which drives belt 33 running around belt pulley 46 fixed on spindle 30, belt pulley 67 having spindle 63 of roller 62, thence around wheel 68^a (which drives the back pressure roller by means of a flexible shaft, see Fig. 10), and the driving wheel 99 of the stacker shaft 98.

The shaft 43 of the separator roller 42 and the shaft 66 of the roller 65 are flexible.

Mail dropped into the feeding trough is carried by the belt running at the bottom of the feeding trough to the first separating roller one or more letters at a time according to the length of the feeding trough and the number of men engaged in facing mail.

The rough separation at the first separating roller frequently results in mail overlapping, that is to say, mail is separated for a portion of its length only and it is this peculiarity which being inseparable from an automatic device of that kind is provided for throughout the machine and which distinguishes it from others. In an automatic device it is evident that there must be sufficient lightness of tensioning of rollers usually loosely mounted not to retard diverse thickness of mail. In hand feeding this difficulty is overcome by varying pressure of the hand.

Assuming that two pieces of mail in this machine are only partially separated, say that the second piece is overlapping by one half the first piece, the two pieces will pass between the rollers in the same way. The mail is then projected toward the next forward pair of rollers. The feeding band lengthwise is suitably arranged provided

with a feeding surface and as a rule will advance the first piece of mail to some extent, the second piece being retarded by a spring. The second separating roller will further retard the second letter and in the great majority of such cases will do so until the first letter has passed toward the marking rollers. If the separation is incomplete it is of no consequence for the reason that the marking roller is on the right hand side of the letter path. The mail therefore passes between the marking rollers with its blank end (that is the end which does not bear the postage stamp) first. The first piece of mail will be marked for its entire length as the marking is continuous, and the second piece will be marked say for three fourths of its length and the marking will necessarily cover the postage stamp.

When the machine is required to be used for hand feeding the adjustable guide plate 81 is removed.

In Fig. 11 a modification is shown involving a supplementary guide 110 similar to the device 81 of Fig. 1, and a supplementary roller 111 is indicated actuated by means of a belt driven from the pulley 29. In Fig. 12 a modification is indicated whereby the feeding trough belt 7 is carried forward to the second separator roller 65.

Obviously other modifications and extensions will occur to those skilled in the art without in any manner departing from the spirit of my invention.

Having now described my invention, what I claim as new and desire to secure by Letters Patent is:—

1. In a mail marking machine, a mail-marking table, roller type marking mechanism at one end of said table on the right hand side of the letter path, a belt pulley at the other end of said table, a second belt pulley adjoining said roller type marking mechanism, a feed belt on said first and second belt pulleys, a tension roller for said belt midway the said first and second belt pulleys, a spring adjustable guide plate at an acute angle with said feed belt, a separator roller opposite said first belt pulley, a separator roller opposite said second belt pulley, and means for driving said belt pulleys and roller marking mechanism substantially as described.

2. In a mail marking machine, a mail marking table, roller type marking mechanism at one end of said table on the right hand side of the letter path, a belt pulley at the other end of said table, a second belt pulley adjoining said roller type marking mechanism, a feed belt on said first and second belt pulleys, a tension roller for said belt midway the said first and second belt pulleys, a feed roller opposite to said tension roller, a spring adjustable guide plate at an acute angle with said first belt pulley,

and means for driving said belt pulleys and roller type marking mechanism substantially as described.

3. In a mail marking machine, a mail marking table, roller type marking mechanism at one end of said table on the right hand side of the letter path, a belt pulley at the other end of said table, a second belt pulley adjoining said roller type marking mechanism, a feed belt on said first and second belt pulleys, a tension roller for said feed belt midway the said first and second belt pulleys, a feed roller opposite to said tension roller, a spring adjustable guide plate at an acute angle with said feed belt, a separator roller opposite said first belt pulley, and means for driving said belt pulleys and roller type marking mechanism substantially as described.

4. In a mail marking machine, a mail marking table, a roller type marking mechanism at one end of said table on the right hand side of the letter path, a belt pulley at the other end of said table, a second belt pulley adjoining said roller type marking mechanism, a feed belt on said first and second belt pulleys, a tension roller for said feed belt midway the said first and second belt pulleys, a feed roller opposite to said tension roller, a spring adjustable guide plate at an acute angle with said feed belt, a separator roller opposite said first belt pulley, and means for driving said belt pulleys and roller type marking mechanism substantially as described.

5. In a mail marking machine, a mail marking table, roller type marking mechanism at one end of said table on the right hand side of the letter path, a belt pulley at the other end of said table, a second belt pulley adjoining said roller type marking mechanism, a feed belt on said first and second belt pulleys, a tension roller for said feed belt midway the said first and second belt pulleys, a feed roller opposite to said tension roller, a spring adjustable guide plate at an acute angle with said feed belt, and means for driving said belt pulleys and roller type marking mechanism substantially as described.

at the other end of said table, a second belt pulley adjoining said roller type marking mechanism, a feed belt on said first and second belt pulleys, a tension roller for said feed belt midway the said first and second belt pulleys, a feed roller opposite to said tension roller, a spring adjustable guide plate at an acute angle with said feed belt, a separator roller opposite said first belt pulley, and means for driving said belt pulleys and roller type marking mechanism substantially as described.

6. In a mail marking machine, a mail marking table, roller type marking mechanism at one end of said table on the right hand side of the letter path, a belt pulley at the other end of said table, a second belt pulley adjoining said roller type marking mechanism, a feed belt on said first and second belt pulleys, a tension roller for said feed belt midway the said first and second belt pulleys, a feed roller opposite to said tension roller, a spring adjustable guide plate at an acute angle with said feed belt, a separator roller opposite said first belt pulley, a separator roller opposite said second belt pulley, and means for driving said belt pulleys and roller type marking mechanism substantially as described.

In testimony whereof I affix my signature in presence of two witnesses.
